Primary Examiner — Cathron C Brooks*Assistant Examiner* — W. A. Teddy Falloway(74) *Attorney, Agent, or Firm* — Tredecim LLC; Sean L. Sweeney; Taylor A. Noonan**CLAIM**

The ornamental design for an expanding cargo bin, as shown and described.

DESCRIPTION

FIG. 1 is a front view of an expanding cargo bin showing our new design;

FIG. 2 is a rear view thereof;

FIG. 3 is a left side view thereof;

FIG. 4 is a right side thereof;

FIG. 5 is a bottom view thereof;

FIG. 6 is a top view thereof; and,

FIG. 7 is a perspective front view thereof.

The broken lines shown in the drawings illustrate portions of the expanding cargo bin that form no part of the claimed design.
